COMBINED PROGRAMMABLE CONTROLLER AND POWER SUPPLY THEREFOR

Robert J. Mauceri, North Reading, and Charles F. Midleton, Jr., Sudbury, Mass., assignors to Modicon Corporation, Andover, Mass.

Filed Apr. 23, 1974, Ser. No. 463,258

Term of patent 14 years

Int. Cl. D14—02

U.S. Cl. D26—5 C

FIG. 1

FIG. 3

FIG. 2

FIG. 4

FIG. 5

FIG. 6

FIG. 7

FIG. 8

FIG. 9

FIG. 10

FIG. 1 is a front perspective view of a programmable controller embodying our new design;

FIG. 2 is a front perspective view of the controller portion of the unit, shown on a slightly enlarged scale;

FIG. 3 is a front perspective view of the power supply portion of the unit, shown on a slightly enlarged scale;

FIG. 4 is a plan view of the power supply shown on an enlarged scale;

FIG. 5 is a rear elevational view;

FIG. 6 is a bottom plan view of the power supply of FIG. 3;

FIG. 7 is a side elevational view of the power supply of FIG. 3;

FIG. 8 is a rear elevational view of the controller, shown on an enlarged scale;

FIG. 9 is a side elevational view thereof, the opposite side being a mirror image thereof; and

FIG. 10 is a top plan view of the controller of FIG. 2. In FIGS. 2, 8, 9 and 10, the power supply portion of the unit has been omitted for ease of illustration, and in FIGS. 3, 4, 5, 6 and 7, the controller portion of the unit has been omitted for ease in illustration.

We claim:

The ornamental design for a combined programmable controller and power supply therefor, substantially as shown and described.
